ELECTRIC PLUG LIFTER

James J. Sheeran, Brooklyn, N. Y.

Application August 18, 1936, Serial No. 96,688

4 Claims. (Cl. 173—361)

My invention relates to attachment plugs and more particularly to means to facilitate removal of attachment plugs and the like from their associated receptacles or sockets.

It frequently happens, in the use of conventional attachment plugs, that the operator removes the top or cap portion from the plug base or from a wall receptacle by pulling on the electrical cord. This is not only injurious to the cord, but it also tends to loosen the terminals. If the pull is not in a direction normal to the receptacle, the contacts are liable to become bent and if the connection is with a heating unit, for example an electric iron or other high resistance piece, there may be considerable arcing which creates a fire hazard. Various means have been adapted to prevent loosening of the cord terminals and to prevent strain on the portion of the cord interiorly of the plug cap and the screw terminals to which the conductors are attached. A conventional method comprises forming a knot at the end of the cord which is adapted to seat in the recessed portion of the cap and sometimes a strain insulator is attached directly to the cord within the cap. While these devices overcome the tendency of breaking or separating the cord from the terminals, they will not prevent injury to the contact blades when the operator withdraws the attachment plug cap by pulling on the cord, in a direction at an angle to the plane of contact surface of the plug or receptacle.

Heretofore, it has been proposed to provide means for releasing attachment plugs from their sockets or receptacle by using devices designed to exert a pressure between the cap and its socket or receptacle. In accordance with one arrangement, the cap is provided with a bell crank device built into the body of the attachment plug cap; it has also been suggested to use a piston or plunger adapted to slide longitudinally of the plug body, and the caps have been formed with handle members exteriorly thereof, adapted to be grasped by the operator, for the purpose of withdrawing them from a receptacle. While the prior art devices will no doubt operate to release a cap from its plug or receptacle, they are open to several objections. As far as I am aware, they have all heretofore been built into the plug, that is, formed integrally with the cap member. If the attachment plug becomes damaged, it is necessary not only to discard the plug but also the lifting device associated therewith. In those devices in which a bell crank arrangement is used, the forces exerted between the receptacle and the cap are not uniformly distributed, a quick

break is not always obtained when it is attempted to release the plug and further there is a possibility of short circuiting the blade contact members of the plug.

It is the purpose of the present invention, to overcome the difficulties encountered in the prior art devices enumerated above, and to provide a lifting device, in the form of an attachment adapted to be quickly and easily mounted exteriorly of a plug cap, radio tube base, or the like. The device is of general application in connection with various types of separable electrical connectors. It consists of but few parts, is strong and sturdy in construction and not liable to get out of order even after long and continued use.

An object of my invention is to provide an attachment for disconnectable parts of electrical connectors, wherein the separable or removable portion of the connector may be quickly and easily disconnected from its cooperative receptacle or socket.

Another object of my invention is to provide a detachable lifting device for attachment plugs, whereby a plug may be easily released and disconnected from its associated socket or receptacle.

Yet another object of my invention is to provide an attachment for disconnectable parts of electrical connectors, wherein the separable or removable portion of the connector may be forced outwardly away from the normal operative position in its associated socket or receptacle.

Still another object of my invention is to provide an attachment for disconnectable parts of electrical connectors, for example attachment plugs and the like, constructed and arranged whereby the removable portion of the connector may be lifted from its cooperative receptacle without the necessity of exerting any pull or strain on the electrical conductors associated with the removable portion of the plug.

A further object of my invention is to provide an attachment for disconnectable parts of electrical connectors, for example attachment plugs and the like, designed to provide a quick break between the electrical contacts whereby arcing is substantially completely eliminated.

With these and other objects in view, which may be incident to my improvements, the invention consists in the parts and combinations to be hereinafter set forth and claimed, with the understanding that the several necessary elements, comprising my invention, may be varied in construction, proportions and arrangement, without

departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

10 In the drawing:

Figure 1 is a plan view of an attachment plug associated with a wall or baseboard receptacle and provided with one form of lifting device.

Fig. 2 is a front elevational view of the arrangement shown in Figure 1.

Fig. 3 is an elevational view of an attachment plug equipped with my improved lifting device.

Fig. 4 is an elevational view of a radio tube equipped with a lifting device.

20 Fig. 5 is an elevational view of an electrical connector, showing a modified form of lifting device.

Fig. 6 is a plan view of the arrangement shown in Fig. 5.

25 Fig. 7 is a side elevational view of another modification of the lifting device; and

Fig. 8 is a front view of the arrangement shown in Fig. 7.

Referring to the drawing and more particularly to Figures 1 and 2, there is shown a wall or baseboard receptacle designated generally by numeral 1, the opening to the interior of the receptacle being covered by means of a suitable plate 2. Seated in electrical connection with the contacts of the receptacle is an attachment plug member having a body portion 3 and contact members 4 adapted to frictionally engage with the contacts, not shown, of the receptacle. Attached to the body portion 3 of the plug is a lifting device comprising a base member 5 having a pair of symmetrical arcuate shaped arms 6 pivotally mounted thereon at diametrically opposite points 7. The arm members are formed with cam surfaces 8 and are interconnected by means of cross-piece designated generally by numeral 9, the cross-piece being bent to form a lip or flange portion 10, adapted to serve as a handle or gripping member for the purpose of moving the arms of the plug lifter about their pivotal points.

50 The base 5 of the lifting device is designed to encircle the body portion 3 of the attachment plug cap and is detachably clamped thereon by means of set screws 11 and adjustable nuts 12. The lifting device may be made of metal or other suitable material of sufficient thickness to provide necessary rigidity so that the arms will not become bent or distorted in the normal operation of the device. In order to remove an attachment plug cap from its seated position in a receptacle or plug, the arms 6 are turned in a direction of the receptacle by exerting a pressure on handle or grip member 10, the cam surfaces 8 of the arms then contacting with the surface of the receptacle, thus forcing the cap outwardly from its seated position thereon.

70 It will be noted that in my improved plug lifting device, the force exerted on the plug cap is distributed equally and uniformly through the pivotal points and movement of the plug away from the receptacle is effected in a direction normal to the plane of the receptacle contacts. In other words, due to the design and configuration of the cam surfaces, and by spacing the 75 arms equidistant from the center of the cap, uni-

form distribution of the forces is obtained, with the result that the plug is forcibly pulled away from the receptacle in the same manner as if the pull were exerted on the cord, but without the danger of loosening the cord contacts or bending the blade members. It will be further noted in connection with cam surfaces 8, that they are designed to provide a positive lifting of the cap substantially as soon as they contact the surface of the receptacle, insuring a quick breaking of the contacts for the purpose of reducing arcing to a minimum.

Referring to Fig. 3, there is shown an attachment plug comprising a cap member 13 and a threaded base 14. In this arrangement the lifting device, which is the same as that described in connection with arrangements shown in Figures 1 and 2, is attached to the body portion of cap 13 by means of set screws 15, the cam surfaces 8 of arms 6, being adapted to contact with the periphery of the threaded base 14, when the arms are turned downwardly against the base member. In Fig. 4, there is shown a thermionic tube 16 equipped with a lifting device. The base 5 of the lifter is clamped to the base portion of the tube and when it is desired to remove the tube from its socket or receptacle the cam portions of the arcuate arms contact with the supporting base or plate for the tubes, thus forcibly lifting the tubes out of their sockets.

Referring to Fig. 5, there is shown a modified form of plug lifter adapted for use in connection with a larger type attachment plug or connector, and more particularly plugs of the character used for making connection with devices requiring a comparatively high current. In this arrangement, the arms are attached to vertical members 17, formed by bending the base 5 upwardly at a right angle to the plane of the base. The connector, which is of conventional construction, comprises an upper portion 18, and base 19 having contact blades or elements 20. The horizontal portions 5 of the lifting device base 5 may be conveniently attached to the plug by inserting them between the separable parts of the plug and using the standard set screws or bolts 21, associated with the plug parts for the purpose of holding the lifting device base in fixed position.

Referring to Figs. 7 and 8 there is shown a modified form of attachment plug cap lifting device, wherein the arms are formed with double arcuate or cam portions. In this arrangement, base member 5 of the lifting device is the same as that described in connection with the device shown in Figures 1 and 2, however, it will be noted that the arm members 6 are provided with arcuate portions 8' which are substantially in the shape of a semi-circle, so that the plug cap may be lifted from its receptacle by rotating the arms about their pivotal points in either direction. By means of this arrangement the plug can be inserted in a receptacle without regard to the position of the arcuate portion of the arms. It will be further noted that the arm members 6 are provided with looped portions 22 and 23 formed by expanding the material of one of the arms and the cross piece respectively. The purpose of the looped portions is to provide a support and strain resistor for the cord 24 associated with the plug cap. The cord is adapted to be threaded through loop 22 and may be conveniently tied or looped around portion 25 of loop member 23.

While I have shown and described the preferred

embodiment of my invention, I wish it to be understood that I do not confine myself to the precise details of construction herein set forth, by way of illustrations as it is apparent that many changes and variations may be made therein, by those skilled in the art, without departing from the spirit of the invention, or exceeding the scope of the appended claims.

What I claim is:

- 10 1. An electrical connector including a body portion having contact members adapted to frictionally engage with contacts of a cooperative receptacle, means mounted externally of said body portion adapted to forcibly disconnect the contact members, comprising a base, means to readily detach said base from the body portion of the connector and a crank member having a pair of symmetrical arcuate shaped arms providing cam surfaces pivotally attached to the base at diametrically opposite points, the cam surfaces of said arms contacting with the associated receptacle when the arms are moved about their pivotal points in the direction of the receptacle.
- 15 2. An electric connector, including a body portion having contact members adapted to frictionally engage with contacts of a cooperative receptacle, means mounted externally of said body portion adapted to forcibly disconnect the contact members, comprising a split ring adapted to encircle the body portion of the connector, means to clamp the ring in operative position on said body portion, and a crank member pivotally mounted upon the ring, said crank member having an arm formed with a cam surface, said cam
- 20 surface of the arm contacting with the associated
- 25
- 30
- 35

receptacle when the portion of the arm remote from the cam surface is moved about its pivotal point in the direction of the receptacle.

3. An electric connector, including a body portion having contact members adapted to frictionally engage with contacts of a cooperative receptacle, means mounted externally of said body portion to forcibly disconnect the contact members, comprising a split ring adapted to encircle the body portion of the connector, means to clamp the ring in operative position on said body portion, and a crank member pivotally mounted upon the ring, said crank member having a pair of arms each formed with a cam surface, the cam surfaces contacting with the associated receptacle when the portions of the arms remote from the cam surfaces are moved about their pivotal points in the direction of the receptacle.

4. An electric connector, including a body portion having contact members adapted to frictionally engage with contacts of a cooperative receptacle, means mounted externally of said body portion to forcibly disconnect the contact members, comprising a split ring adapted to encircle the body portion of the connector, means to clamp the ring in operative position on said body portion, and a crank member having a pair of symmetrical arcuate shaped arms providing cam surfaces pivotally attached to the base at diametrically opposite points, said cam surfaces contacting with the associated receptacle when the portions of the arms remote from the cam surfaces are moved about their pivotal points in the direction of the receptacle.

JAMES J. SHEERAN.
